CONTROL PANEL FOR A CLOTHES WASHING MACHINE

Henry Dreyfuss, South Pasadena, Calif., and Robert H. Hose, Mountainside, N.J., assignors to The Hoover Company, North Canton, Ohio, a corporation of Ohio

Filed Nov. 3, 1960, Ser. No. 62,718

Claims priority, application Great Britain May 12, 1960

Term of patent 14 years

(Cl. D49—1)

Fig. 1

Fig. 3

Fig. 4

Fig. 2

FIGURE 1 is a front perspective view of a control panel for a clothes washing machine, showing our new design;

FIGURE 2 is an enlarged front elevational view thereof;

FIGURE 3 is an enlarged vertical section on line 3—3 in FIGURE 2, and

FIGURE 4 is a vertical sectional view taken on the line 4—4 in FIGURE 2.

The dotted line showing of a clothes washing machine in FIGURE 1 is for illustrative purposes only.

We claim:

The ornamental design for a control panel for a clothes washing machine, substantially as shown and described.
